[57] ABSTRACT

An improved elevator control system for maintaining a properly controlled interval between a plurality of elevator cars. The system includes means for detecting the time interval or spatial interval between a preceding elevator car, an intermediate elevator car and a succeeding elevator car. When the interval between the preceding and intermediate elevator cars is more than the interval between the intermediate and succeeding elevator cars, the intermediate elevator car is accelerated, while when the former interval is less than the latter interval, the preceding or succeeding elevator car is accelerated for maintaining a reasonable interval between these elevator cars.

ELEVATOR CONTROL SYSTEM

This invention relates to an elevator control system and more particularly to improvements in an elevator control system for controlling the operation of a plurality of elevator cars servicing a plurality of service floor landings.

In a building in which a plurality of elevator cars are in parallel operation for servicing a plurality of service floor landings, the elevator cars must be prevented from "bunching," namely, servicing together without any interval therebetween. In other words, it is necessary to maintain a suitable interval between the elevator cars. The intervals between these elevator cars need not be equal to each other and are desirably such that the passengers in a plurality of elevator halls wait an equal period of time.

Reasonable intervals between servicing elevator cars may be obtained by accelerating at least one of the elevator cars on the basis of information including, the intervals between the elevator cars, the hall calls originating from the floors, etc. The acceleration of a specific elevator car may be attained by limiting its response to forward hall calls originating from the floors lying within a predetermined range, from the position of a specific elevator car indicated by a position signal (which will be described in detail later), thereby apparently advancing the position of the elevator car, or preventing the elevator car from responding to such forward hall calls until a predetermined condition is satisfied.

The position signal above described may represent the floor number or space, but it is preferable for practical purposes that the position signal represents the floor number. When the position signal indicates the floor number, it represents the actual position of the elevator car and is thus called a physical position signal. When one of the elevator cars is at rest at a floor, the position signal may represent the floor at which it is at rest. In this case, this floor coincides with the physical position of the elevator car. When the elevator car is moving, the position signal may represent a floor which is forward relative to the physical position of the elevator car. For example, such a floor may be the fourth floor when the elevator car is moving past the third floor at a low speed, or the fifth floor when the elevator car is moving past the third floor at a medium speed, or the sixth floor when the elevator car is moving past the third floor at a high speed. The same applies to the position signal representing the space.

In a typical elevator control, an elevator car responds to up hall calls from the upper floors when it is moving upward and responds to down hall calls from the lower floors when it is moving downward. Therefore, when the first floor is the dispatching floor (bottom terminal) for the elevator cars, each elevator car responds first to an up call from the bottom terminal and then responds successively to up calls from the upper floors, and after arriving at the top terminal floor, responds first to a call from the top terminal floor and then responds successively to down calls from the lower floors. Thus, when a certain floor is taken as a reference floor, the floors lying forward of the reference floor in the moving direction of the elevator car are called forward floors and the hall calls from such floors are called forward hall calls, while the floors lying behind the reference floor in the moving direction of the elevator car are called

back floors and the hall calls from such floors are called back hall calls. For example, when the fifth floor is taken as a reference floor and the elevator car is moving upward, the up call from the sixth floor is a forward hall call and the up call from the third floor is a back hall call. When the elevator car is moving downward, the down call from the sixth floor is a back hall call and the down call from the third floor is a forward hall call.

- 10 The elevator car responds commonly to forward hall calls from the floors lying forward of the position represented by the position signal, but when the elevator car is arranged so as not to respond to forward hall calls from the floors lying within a specific range, this elevator car is apparently advanced in its position and its movement is accelerated. In this description, the nearest floor to which the elevator car can actually respond is called a provisional position. Thus, the provisional position coincides with the physical position represented by the position signal when no limitation is applied to the forward hall calls, while the provisional position is ahead of the physical position when the elevator car is apparently advanced in its position. On the other hand, the provisional position is not definitely determined when the elevator car is arranged so as not to respond to all the hall calls including those from the floors lying within the specific range until a predetermined condition is eliminated.
- 15 20 25

- 30 In the arrangement in which means for accelerating the elevator cars are provided for apparently advancing the position of the elevator cars over a predetermined range, the service zone to which each individual elevator car should respond can be definitely determined. However, the service zone to be served by each individual elevator car is indistinct when arrangement is made so that at least one suitable elevator car is prevented from responding to all the hall calls until disorderly movement of the elevator cars is eliminated. The former arrangement requires means for determining whether or not each individual elevator car should respond to the hall calls from the floor. In the latter arrangement, control means for controlling the elevator cars as to whether or not each individual elevator car should respond to all the hall calls can be simplified in structure, but it is necessary to determine the elevator car which should respond to a hall call originating from a specific floor.
- 35 40 45

- 50 55 It is therefore an object of the present invention to provide an elevator control system for controlling the operating condition of elevator cars depending on the traffic so as to operate the elevator cars in suitably spaced relation from each other thereby to substantially equalize the waiting time for the passengers waiting in the elevator halls.

- Another object of the present invention is to provide an elevator control system which eliminates undesirable bunching of continuously moving elevator cars so as to improve the operating efficiency.

- A further object of the present invention is to provide an elevator control system having means for detecting the disorderly movement of elevator cars so as to prevent at least one of the elevator cars from responding to all the hall calls in the event of occurrence of such disorderly movement, means are provided for immediately selecting one of the elevator cars which can respond to a hall call in response to the registration of such a hall call.
- 60 65

One feature of the present invention resides in the fact that, when the interval between a preceding elevator car and a succeeding elevator car exceeds a predetermined limit, the succeeding elevator car is accelerated to maintain a reasonable interval therebetween.

Another feature of the present invention resides in the fact that, when the interval between a preceding elevator car and an intermediate elevator car among three elevator cars exceeds the interval between a succeeding elevator car and the intermediate elevator car by more than a predetermined limit, the intermediate elevator car is accelerated to maintain a reasonable interval between it and the preceding elevator car, while when the interval between the succeeding elevator car and the intermediate elevator car exceeds the interval between the preceding elevator car and the intermediate elevator car by more than the predetermined limit, the preceding elevator car or succeeding elevator car is accelerated to maintain a reasonable interval between it and the intermediate elevator car.

A further feature of the present invention resides in the fact that an elevator car applied with an acceleration command signal does not respond to any forward or back hall calls during the period of time in which the acceleration command signal is continuously applied.

For a full understanding of the nature and objects of the present invention, reference should be had to the following detailed description taken in conjunction with the accompanying drawings, in which:

FIGS. 1a and 1b are schematic diagrams showing the running state of a plurality of elevator cars;

FIG. 14 is a circuit diagram showing the structure of one form of means for calculating the distance between the elevator cars and a specific floor;

FIG. 15 is a circuit diagram showing in detail the structure of one form of a minimum selector; and

FIGS. 16 and 17 are block diagrams showing partial modifications of the system according to the present invention.

Referring to FIGS. 1a and 1b, the present invention 10 will be described with reference to an elevator system in which three elevator cars A, B and C are provided in a building having 10 floors designated by F1 to F10. The physical positions of the elevator cars A, B and C are designated by 1U to 9U when they move upward 15 and by 10D to 2D when they move downward.

There are various methods for detecting the disorderly movement of these elevator cars and correcting the disorder to obtain a reasonable interval therebetween. According to one method in which two out of 20 the three elevator cars are considered, the position signals representing the physical positions of the two elevator cars are generated and the preceding elevator car is accelerated when the difference between the position signal representing the position of the preceding elevator car and the position signal representing the position of the succeeding elevator car becomes smaller than a predetermined limit. On the other hand, the succeeding elevator car is accelerated when the difference between the position signals exceeds the predetermined 25 limit.

According to another method in which all of the 30 three elevator cars are considered, the intermediate elevator car is accelerated when the interval between the preceding and intermediate elevator cars exceeds the interval between the intermediate and succeeding elevator cars. On the other hand, the succeeding or preceding elevator car is accelerated when the interval between the succeeding and intermediate elevator cars 35 exceeds the interval between the intermediate and preceding elevator cars.

According to a further method in which each individual elevator car is considered, each individual elevator car is accelerated when it is delayed by a predetermined time from a predetermined running schedule. Each individual elevator car is accelerated when disorder occurs in the arrival of the elevator cars at different floors.

Further, in addition to the spatial distance between the elevator cars as described above, the concept of the time distance taking into consideration the function of time associated with the number of stoppages of the elevator cars may be introduced for effectively controlling the operation of the elevator cars.

FIG. 2 is a block diagram showing the structure of an embodiment of the present invention in which the three elevators cars servicing the building having 10 floors are adapted to be controlled by the second method above described.

Position detectors DA, DB and DC for the respective elevator cars A, B and C generate position signals FA, FB and FC representing the physical positions of the respective elevator cars A, B and C. A hall call register HCR stores hall calls HC1U (up hall call from the first floor) to HC9U and HC10D (down hall call from the tenth floor) to HC2D. The hall call register HCR is reset by a reset signal RE1 upon arrival of the elevator

car at the specific floor from which the hall call is originated.

An interval calculating order selector STS selects only one of the hall calls registered in the hall call register HCR. That is, the first hall call of all arriving at the hall call register HCR is selected by the interval calculating order selector STS. In response to the application of the signal selected by the interval calculating order selector STS to an interval calculating commander STC, the latter generates command signals SG1, SG2 and SGR at intervals of a predetermined period of time. Interval detectors SEA, SEB and SEC compare the position signals FA, FB and FC representing the physical positions of the respective elevator cars A, B and C with the floor from which the hall calls originated and selected by the interval calculating order selector STS and calculate the backward intervals between the specific floor and the elevator cars. The interval calculation is carried out in the manner described with reference to FIGS. 1a and 1b. Suppose, for example, that the selected hall call is HC6U meaning that a passenger wants to go upward from the sixth floor, and the elevator cars are moving upward as illustrated in FIGS. 1a and 1b, then the intervals between the sixth floor and the nearest elevator car B, intermediate elevator car C and remotest elevator car A are detected. In this case, it is to be understood that the interval includes the spatial distance and the time distance. The command signal SG1 is applied from the interval calculating commander STC to gates GA, GB and GC. This command signal SG1 is desirably generated after a period of time required for the calculation by the interval detectors SEA, SEB and SEC. In response to the application of the command signal SG1 to the gates Ga, GB and GC, the outputs from the interval detectors SEA, SEB and SEC are applied to respective gates PGA, PGB and PGC which are controlled by acceleration signals. These acceleration signals are produced in a manner which will be described later. The elevator car having been accelerated already does not respond to the hall call from the specific floor regardless of a large or small interval therebetween. In other words, among the gates PGA, PGB and PGC, the one having been accelerated is in the closed condition. A minimum selector DM selects a minimum output among the outputs from the gates PGA, PGB and PGC. Thus, the elevator car is selected which is spaced a minimum backward interval from the specific floor from which the hall call is originated and which has not been applied with the acceleration signal. The minimum selector DM generates a signal SA, SB or SC representative of the selected elevator car. A response display RD at the floor from which the hall call is originated and registered displays the selected elevator car and thus a passenger waits at the landing station for that elevator car. The interval calculating commander STC generates the command signal SG2 which is delayed by a predetermined period of time from the first command signal SG1. This period of time is set so as to be sufficient for selecting the responding elevator car. In response to the application of the command signal SG2 to gates RGA, RGB and RGC which have been already applied with the other two signals, one of the gates RGA, RGB and RGC is opened so that the hall call, for example, HC6U selected by the interval calculating order selector STS is registered in one of running call registers RUNA, RUNB and RUNC to stop the selected elevator car. Suppose, for example,

that the elevator car B is selected in response to the hall call HC6U. In this case, the gate RGB is opened and the signal demanding up service from the sixth floor or 6U is stored in the running call register RUNB so that the elevator car B is decelerated to stop at the sixth floor. The stoppage of the elevator car B at the sixth floor erases the memory in the register RUNB. Generally, an elevator car must stop as a rule at the floors designated by passengers riding in the cage. To this end, cage calls CCA, CCB and CCC are stored unconditionally in the respective running call registers RUNA, RUNB and RUNC.

With a delay of a predetermined period of time from the command signal SG2, the interval calculating commander STC applies the command signal SGR to the interval calculating order selector STS to reset the latter. The time at which the command signal SGR is generated is determined by taking into consideration the period of time required for completing a series of controls and calculations including the selection of the hall call, selection of the responding elevator car and display of such an elevator car. It will be seen from the above description that one of the elevator cars is specified for a specific hall call in response to the output from the interval calculating order selector STS. When another hall call is registered in the hall call register HCR at the time at which the interval calculating order selector STS is reset, another elevator car is selected in the same manner as above described. When one of the cage calls CCA, CCB and CCC registered in the running call registers RUNA, RUNB and RUNC coincides with the specific hall call requesting the stoppage at the same floor, the corresponding gate PGA, PGB or PGC may be opened independently of the appearance of the acceleration signal.

The interval between two elevator cars, for example, the elevator cars A and B in FIGS. 1a and 1b can be sought in various ways. However, the most accurate method is to seek the period of time or time interval required for the elevator car B to reach the position of the elevator car A. This time interval T_{ab} is approximately given by the following equation:

$$T_{ab} = K_1 D_{ab} + K_2 C_{ba} \quad (1)$$

where K_1 and K_2 are constants determined from various factors, D_{ab} is the physical distance between the elevator cars A and B which is equal to a four-floor distance in FIGS. 1a and 1b, and C_{ba} is the number of stoppage, in response to cage calls and hall calls, of the elevator car B until it reaches the position of the elevator car A. $K_1 D_{ab}$ and $K_2 C_{ba}$ will hereinafter be called a spatial distance and a time distance, respectively. Similarly, the time interval T_{bc} between the elevator cars B and C is approximately given by the following equation:

$$T_{bc} = K_1 D_{bc} + K_2 C_{cb} \quad (2)$$

FIG 3a is a block diagram showing the structure of one form of a generator for generating the acceleration signals SHA-A to SHC-A, SHA-B to SHC-B, and SHA-C to SHC-C. This generator is designed to control the elevator cars in accordance with the second method described previously.

The three elevator cars A, B and C are arranged in parallel with one another, and the position detectors DA, DB and DC detect the position of these elevator cars A, B and C to deliver the position signals FA, FB and FC representative of the physical positions of the elevator cars A, B and C respectively. These position signals FA, FB and FC are applied to interval detectors EA, EB and EC associated with the respective elevator cars A, B and C. In response to the application of the position signals FA, FB and FC, the interval detectors EA, EB and EC generate space signals SSA, SSB and SSC, and signals OBA, OCA, OAB, OCB, OAC and OBC indicative of the succeeding elevator car, for each elevator car respectively. In the present embodiment, the term "succeeding elevator car" is used to denote an elevator car which is nearest to a specific elevator car in the backward direction, and the interval therebetween is detected. However, the succeeding elevator car may be the nearest one in the forward direction and the interval therebetween may be detected.

The position of the elevator car is classified into 1U to 9U when it moves upward and into 1D to 2D when it moves downward as seen in FIGS. 1a and 1b. The space signals SSA, SSB and SSC represent the interval between one elevator car and the succeeding elevator car. Gates G1A, G2A, G1B, G2B, G1C and G2C are used to provide signals SPA, SPB and SPC representative of the interval between one elevator car and the preceding elevator car which is the nearest one in the forward direction. When, for example, the elevator car A is the succeeding elevator car for the elevator car B, the output OAB appears from the interval detector EB. As a result, the gate G1A is opened, and when this occurs, the space signal SPA applied to a comparator SLA is the space signal SSB. This space signal SPA represents the interval between the elevator car A and the preceding elevator car B. Similarly, the signals SPB and SPC representative of the interval between the elevator car B and the preceding elevator car C and between the elevator car C and the preceding elevator car A are produced to be applied to respective comparators SLB and SLC. The comparators SLA, SLB and SLC compare the space signals SSA, SSB and SSC with the space signals SPA, SPB and SPC respectively and apply the acceleration signals SHA, SHB and SHC to hall call response control means MA, MB and MC respectively. The acceleration signal is applied to accelerate one of the elevator cars in the manner described below. Herein, the elevator car which is taken as a reference is called an intermediate elevator car.

1. The intermediate elevator car is accelerated when the interval between the preceding elevator car and the intermediate elevator car becomes larger than the interval between the intermediate elevator car and the succeeding elevator car, that is, for example, when $SPA - SSA > 0$.

2. The succeeding elevator car is accelerated when the interval between the succeeding elevator car and the intermediate elevator car becomes larger than the interval between the intermediate elevator car and the preceding elevator car, that is, for example, when $SPA - SSA < 0$.

3. The preceding elevator car is accelerated when the interval between the succeeding elevator car and the intermediate elevator car becomes larger than the interval between the intermediate elevator car

and the preceding elevator car, that is, for example, when $SPA - SSA < 0$.

Suppose that the elevator cars A, B and C are the intermediate, succeeding and preceding elevator cars respectively as shown in FIGS. 3b, 3c and 3d. The state shown in FIG. 3b corresponds to the condition 1 and the acceleration signal is applied to the intermediate elevator car A. More precisely, since the elevator car A is the succeeding one for the elevator car C, the output OAC appears from the interval detector EC to open the gate G2A. Due to the fact that $SPA - SSA$ is positive, the comparator SLA applies the acceleration signal SHA to the elevator car A. The hall call response control means MA for the elevator car A does not respond to hall calls HCA from all the floors and the elevator car A is accelerated. The state shown in FIG. 3c corresponds to the conditions (2) and (3) and the preceding elevator car C or succeeding elevator car B is accelerated. In the case of FIG. 3d, the comparator SLA does not apply any acceleration signal to any of the elevator cars.

FIG. 4 shows the structure of the position detectors DA, DB and DC for the respective elevator cars for delivering an analog voltage representative of the physical position of these elevator cars. In FIG. 4, the structure of the position detector DC for the elevator car C is especially shown in detail. A switch S1UC is closed only when the position signal FC indicates that the elevator car C moves upward from the first floor. Similarly, switches S2UC to S9UC and S10DC to S2DC are closed depending on the direction of movement of the elevator car C and the position signal FC thereby generated. Switches for the elevator cars A and B are similarly arranged although parts of these switches are merely shown. These switches are connected in series with respective resistors R1UA to R2DA, R1UB to R2DB and R1UC to R2DC. The resistors for each elevator can have a successively increased resistance from the lowest to the uppermost one in that order. These resistors are connected in common to provide inputs to operating units consisting of operational amplifiers OP1A, OP1B and OP1C, and feedback resistors R1A, R1B and R1C respectively. The ratio between the resistances of the resistors R1UA to R2DA, R1UB to R2DB and R1UC to R2DC and the resistances of the feedback resistors R1A, R1B and R1C may be suitably selected so that the operating units deliver an output voltage as seen in FIG. 5. Since the gain of each operational amplifier is negative, the output voltage has naturally a negative value, but in FIG. 5, the absolute value of the output voltage is shown.

The outputs from the operational amplifiers OP1A, OP1B and OP1C are inverted in polarity by respective phase inverting operating units consisting of input resistors R2A, R2B and R2C, feedback resistors R3A, R3B and R3C, and operational amplifiers OP2A, OP2B and OP2C. Thus, the outputs from the operational amplifiers OP2A, OP2B and OP2C are positive as shown. Three sets of output signals A-a and A-b, B-a and B-b, and C-a and C-b are delivered from the operational amplifiers OP1A and OP2A, OP1B and OP2B, and OP1C and OP2C respectively. The signals in each set have an equal magnitude and are opposite in polarity to each other.

FIG. 6 is a circuit diagram showing the structure of one form of a calculator for calculating the spatial distance between the elevator cars. For convenience of

explanation, the calculator is shown as a means for calculating the distance from the elevator car A in the backward direction. Similar calculators are provided for calculating the spatial distance from the elevator cars B and C.

The position signal $A-b$ (negative) for the elevator car A is applied to an operational amplifier OP3A through an input resistor R4A. The position signal $B-a$ (positive) for the elevator car B is applied to the operational amplifier OP3A through another input resistor R5A. The operational amplifier OP3A is provided with a feedback resistor R6A. The combination consisting of the input resistors R4A and R5A, feedback resistor R6A and operational amplifier OP3A acts as an analog adder, and since the gain of the operational amplifier OP3A is negative, its output is $(A-b) - (B-a)$. Thus, the spatial distance between the elevator cars A and B can be measured. Similarly, the output representative of the spatial distance between the elevator cars A and C is derived from an operational amplifier OP4A. The above description has referred to the case in which the absolute value of the position signal for the elevator car A is larger than those for the elevator cars B and C, but malfunction may take place when this condition is not satisfied. When, for example, the elevator car A moves upward from the fifth floor and the elevator car C moves upward from the eighth floor, the output from the operational amplifier OP4A is -3 volts as apparent from the above description. (For simplicity of explanation, it is assumed that one floor distance corresponds to 1 volt in FIG. 5.) This output does not represent the actual spatial distance between the elevator cars A and C, but that the elevator car C is located forward of the elevator car A by three floors. To avoid malfunction, the calculator shown in FIG. 6 employs an analog switch BL2A which is closed only when a positive input voltage is applied thereto so that the negative output is not applied to a minimum value selecting means the structure of which will be described later. Another analog adder is composed of input resistors R13A and R14A, a feedback resistor R15A and an operational amplifier OP6A. The output from the operational amplifier OP4A and a position signal $A-a$ of E_1 or 18 volts (FIG. 5) corresponding to the S2D position of the elevator car are applied to this analog adder so that the operational amplifier OP6A delivers an output of $18-3=15$ volts. Thus, the calculation shows that the elevator car C is located at a position spaced from the elevator car A by fifteen floors in the backward direction. In this way, the backward spatial distance between the elevator cars A and C can be measured. Similarly, the backward spatial distance between the elevator cars A and B can be measured by means of an analog adder composed of resistors R10A, R11A and R12A and an operational amplifier OP5A. These spatial distance signals are applied to a minimum value selecting means composed of diodes D1A, D2A, D3A and D4A and a d.c. voltage supply of E_2 volts connected to these diodes through a resistor R16A. Thus, the spatial distance between the elevator car A and the nearest or succeeding elevator car located backward of the elevator car A.

When, for example, the spatial relation among the elevator cars is as shown in FIG. 7a, the diode D1A among the diodes D1A to D4A conducts because a minimum positive potential appears at its cathode. The anodes of the diodes D1A to D4A are maintained at the

same potential as the potential at the cathode of the diode D1A since these diodes are connected in common at their anodes. Therefore, the diodes D2A to D4A are not conducting. The anode potential at the diode is derived through a diode D5A so that the spatial distance between the elevator car A and the nearest or succeeding elevator car can be detected. Then, the succeeding elevator car is detected by minimum selecting means composed of a sign converter PCA, comparators CP1A, CP2A, CP3A and CP4A, and OR elements OR1A and OR2A. The anode voltage at the conducting diode is higher than the cathode voltage by an amount corresponding to the forward voltage drop. Therefore, the diode among these diodes conducts, in which the difference between the potential at the anode and the potential at the cathode is smaller than the forward voltage. When, for example, the elevator car B is the succeeding elevator car, the diode D1A is only conducting and an output appears from the comparator CP1A. As a result, the output OBA appears from the OR element OR1A indicating that the elevator car B is the succeeding elevator car, and at the same time, the output representative of the spatial distance between the elevator cars A and B appears from the diode D5A. The sign converter PCA is provided to invert the polarity of one of the two inputs to the comparators CP1A to CP4A so that these two inputs are of opposite polarity.

FIG. 8 is a circuit diagram showing in detail the structure of a calculator for calculating the time distance related to the number of stoppages of the succeeding elevator car. A position signal F1UA is generated when the elevator car A stays at the first floor and is set for upward movement. Similarly, position signals F2UA to F9UA are generated when the elevator car A stays at the second to ninth floor respectively and is set for upward movement. Conversely, when the elevator car A stays at the second to tenth floor and is set for downward movement, position signals F2DA to F10DA are generated respectively. Time distance calculators for the elevator cars B and C are similar to the time distance calculator for the elevator car A. Position signals F1UB to F9UB and F2DB to F10DB are generated for elevator car B, while position signals F1UC to F9UC and F2DC to F10DC are generated for the elevator car C.

The position signals F1UA to F9UA and F2DA to F10DA are applied to respective OR elements O1UA1 to O9UA1 and O2DA1 to O10DA1 as one of two inputs to the latter. The position signals representing the same travelling direction and same floor position of the elevator cars B and C are applied in pairs to respective OR elements O1UA2 to O9UA2 and O2DA2 to O10DA2 to provide two inputs to the latter. For example, the position signals F2UB and F2UC are applied to the OR element O2UA2.

Inhibit elements I1UA to I9UA and I2DA to I10DA are connected to the respective OR elements O1UA1 to O9UA1 and O2DA1 to O10DA1 so that the outputs from these OR elements are applied to the input terminal of the respective inhibit elements I1UA to I9UA and I2DA to I10DA, while the output from the OR elements O1UA2 to O9UA2 and O2DA2 to O10DA2 are applied to the inhibit terminal of the respective inhibit elements. The outputs from the inhibit elements are applied to respective AND elements A1UA3 to A9UA3 and A2DA3 to A10DA3 as one of two inputs to the lat-

ter. Hall call signals originated from the floors or cage call signals in the succeeding elevator car are applied to these AND elements as another input thereto. The outputs of these AND elements are connected through respective resistors γ_{1UA} to γ_{9UA} and γ_{2DA} to γ_{10DA} to a common resistor γ_A to be grounded therethrough. A time distance signal appears across the common resistor γ_A and is related with the number of stoppage of the succeeding elevator car until it reaches the position of the preceding elevator car. The inhibit elements are arranged in the form of a ring in the order of I_{1UA} , I_{2UA} , ..., I_{9UA} , I_{10DA} , I_{9DA} , ..., I_{2DA} and I_{1UA} , and their output are applied as one of inputs to the OR elements O_{1UA1} to O_{9UA1} and O_{2DA1} to O_{10DA1} associated with the inhibit elements of the preceding stage. For example, the output from the inhibit element I_{1UA} is applied to the OR element O_{2DA1} connected to the inhibit element I_{2DA} .

In FIG. 8, suppose that the elevator car A moves upward at the eighth floor, the elevator car B moves upward at the second floor and the elevator car C moves downward at the fifth floor. In this case, the elevator car B is the succeeding elevator car for the elevator car A. Due to the above physical positions of the elevator cars A, B and C, the position signals F_{8UA} , F_{2UB} and F_{5DC} are generated. At first, the OR element O_{8UA1} is turned on the response to the application of the position signal F_{8UA} and an output appears from the inhibit element I_{8UA} . The output from the inhibit element I_{8UA} is applied to the OR element O_{7UA1} (not shown) connected to the inhibit element I_{7UA} (not shown) in the preceding stage so that this inhibit element I_{7UA} is turned on. Similarly, the inhibit elements I_{6UA} , I_{5UA} , I_{4UA} and I_{3UA} (not shown) are turned on. The output from the inhibit element I_{3UA} is applied to the OR element O_{2UA1} which therefore applies an input to the inhibit element I_{2UA} . However, the inhibit element I_{2UA} is not turned on due to the fact that the OR element O_{2UA2} is turned on in response to the application of the position signal F_{2UB} thereby applying an input to the inhibit terminal of the inhibit element I_{2UA} . Thus, the AND elements A_{3UA3} to A_{8UA3} are applied with one of the two inputs thereto. Some of the signals CS_{3U} to CS_{8U} appear in response to hall calls or cage calls in the elevator car B, and the signals thus appearing are applied to the corresponding ones of the AND elements A_{3UA3} to A_{8UA3} so that the corresponding AND elements deliver an output. The voltage appearing across the common resistor γ_A is given by

$$\gamma_o / [\gamma_o + (\gamma/n)] = n\gamma_o / (n\gamma_o + \gamma)$$

where γ is the resistance value of the resistors γ_{1UA} to γ_{9UA} and γ_{2DA} to γ_{10DA} , n is the number of AND elements which are delivering their output, γ_o is the resistance value of the common resistor γ_A , and the output from each AND element is taken as a unit voltage. When the relation between γ_o and γ is selected to be $\gamma_o << \gamma$, the voltage appearing across the common resistor γ_A is given by $n\gamma_o / \gamma$, and the signal thus obtained is proportional to the number n of the AND elements which are in the on state. This number n is equal to the number of stoppages of the elevator car B until it reaches the position of the elevator car A. Each stoppage requires an additional period of time which amounts to the sum of the period of time required for decelerating the elevator

car, the period of time during which the elevator car is held in the stopped state, and the period of time required for accelerating the elevator car. Thus, the time distance is longer than when the elevator car is moving without stopping although the actual spatial distance is short.

FIG. 9 is a block diagram showing the structure of means for controlling the elevator car in response to the acceleration signal. An address composed of input resistors R_{17A} and R_{18A} , a feedback resistor R_{19A} and an operational amplifier OP_{7A} adds the spatial distance to the time distance to calculate the time interval. This time interval SSA between the intermediate elevator car and the succeeding elevator car is compared with the time interval SPA between the intermediate elevator car and the preceding elevator car by comparators CM_{1A} , CM_{2A} , and CM_{3A} . When $SSA - SPA$ is larger than a predetermined value, the comparator CM_{1A} delivers its output or acceleration signal $SHA-A$ which is applied to the elevator car A. When, on the other hand, $SSA - SPA$ is larger than a predetermined value, the comparator CM_{2A} delivers the acceleration signal $SHA-B$ or the comparator CM_{3A} delivers the acceleration signal $SHA-C$. The condition for operation of the comparators CM_{2A} and CM_{3A} is determined by the relative magnitude of the signals SSA and SPA . These acceleration signals $SHA-B$ and $SHA-C$ are applied to the elevator cars B and C respectively. FIG. 9 shows means for controlling the elevator car A which is, in this case, the intermediate elevator car, but it will be seen that similar means are provided for controlling the elevator cars B and C by the acceleration signal.

These acceleration signals are applied as an inhibit input to inhibit elements I_{1UA} to I_{9UA} and I_{10DA} to I_{2DA} (corresponding to respective hall calls) which determine the response to the hall calls. When a hall call is originated from one of the floors, the corresponding one of the signals HC_{1UA} to HC_{9UA} and HC_{10DA} to HC_{2DA} is applied to the associated inhibit element, and the elevator car is decelerated to stop at the floor if no acceleration signal is applied to the elevator car. However, the elevator car is accelerated to maintain the proper interval between it and the other two elevator cars since it does not respond to any hall calls during the period of time in which the acceleration signal is applied thereto.

FIG. 10 is a circuit diagram showing in detail the structure of the interval calculating order selector STS . Although a section STS_{9U} responds to the hall call HC_{9U} , demanding upwards movement from the ninth floor is solely shown in FIG. 10, similar sections are provided to respond to all the hall calls HC_{1U} to HC_{9U} HC_{10D} to HC_{2D} .

When, for example, the hall call HC_{9U} , demanding upwards movement from the ninth floor is registered in the hall call register HCR and is applied to the section STS_{9U} , an AND element A_{9U} delivers an output to set a memory element FF_{9U} such as, for example, a flip-flop. In this case, however, it is assumed that an OR element OR_{9U} is turned off and a NOT element N_{9U} is delivering its output. In response to the appearance of an output from the memory element FF_{9U} , the OR element OR_{9U} is turned on so that a signal SFF_{9U} appears therefrom. This signal SFF_{9U} indicates the fact that the hall call HC_{9U} , demanding upward movement from the ninth floor, is selected. Other selection signals representative of other hall calls are also applied to the

OR element OR9U. Due to, the application of the signal SFF9U to other OR elements (similar to the OR element OR9U) responsive to other hall calls, NOT elements (similar to the NOT element N9U) associated with the respective OR elements are turned off. That is to say, the appearance of the hall call HC9U does not set the memory element FF9U during the period of time in which selection signals representative of other hall calls are present.

After a period of time required for selecting the elevator car responding to the hall call HC9U has lapsed, the reset command signal SGR is applied to the memory element FF9U so that its output disappears. This releases the interlock for the other calculating sections except the section STS9U.

FIG. 11 is a circuit diagram showing the structure of one form of the interval calculating commander STC. An OR element OSTC delivers an output in response to the selection of one of the hall calls or in response to the application of the selection signal SFF9U in this case, and delay means D₁, D₂ and D₃ deliver respective phase-shifted pulses or command signals SG1, SG2 and SGR as shown. In response to the application of the command signal SGR, the memory element FF9U is reset and the signal SFF9U disappears as described already.

FIG. 12 is a circuit diagram showing in detail the structure of means constituting parts of the interval detectors SEA, SEB and SEC shown in FIG. 2 for calculating the spatial distances HSA, HSB and HSC between the elevator cars A, B and C and the floor from which a call is originated. The structure of the means shown in FIG. 12 is generally similar to the means shown in FIG. 6 and comprises resistors R20 to R37, operational amplifiers OP8 to OP13, and analog switches BL3 to BL5. The structure shown in FIG. 12 differs from the structure shown in FIG. 6 in that a signal voltage HCS responsive to a hall call is applied to the operational amplifiers OP8 to OP13. That is, as seen in FIG. 13, a voltage responsive to a specific hall call is generated to be applied to these operational amplifiers. When for example, the hall call HC9U, demanding upward movement from the ninth floor, is selected by the interval calculating order selector STS, a switch SFF9U in FIG. 13 is closed so that an analog signal HCS (corresponding to the voltage at the position S9U in FIG. 5) responsive to the hall call is derived from a potentiometer PME, and this voltage is applied to the operational amplifiers shown in FIG. 12. Thus, the backwards calculated spatial distances HSA, HSB and HSC between the elevators cars A, B and C and the floor at the moment at which the hall call HC9U is originated can be measured on the same principle as that described with reference to FIG. 6. On the other hand, the number of stoppages of the elevator car until it responds to the specific hall call can be measured by means which is similar to the circuit shown in FIG. 8. The structure of this means is shown in FIG. 14. In FIG. 14, hall calls SFF1U to SFF9U and SFF2D to SFF10D specifying the respective floors are applied to the inhibit elements I1UA to I9UA and I2DA to I10DA in lieu of the position signals F1UA to F9UA and F2DA to F10DA for the elevator car A in FIG. 8, and the position signals F1UA to F9UA and F2DA to F10DA for the elevator car A are applied as an inhibit input to the respective inhibit elements. It will be apparent from the description given with reference to FIG. 8 that the ar-

rangement shown in FIG. 14 makes it possible to measure the number of stoppages of the elevator car A until it responds to the specific hall call. The number of stoppage of the elevator cars B and C can be sought by similar means.

The spatial distances and time distances between the elevator cars and the floor from which the hall call is originated can thus be measured by the means shown in FIGS. 12, 13 and 14 and are applied to adders shown in FIG. 15 to seek the time intervals. These adders comprise resistors R41 to R49 and operational amplifiers OP15 to OP17 and generate respective signals MTA, MTB and MTC representative of the time intervals. These signals are applied to the minimum selector

15 DM composed of diodes D10, D11 and D12, a sign converter PC10, and comparators CP5A, CP5B and CP5C when gates GA and PGA, GB and PGB or GC and PGC are opened simultaneously. By this arrangement, the elevator car spaced a minimum time interval from the specific floor is selected in a manner as described in detail with reference to FIG. 2. Thus, the optimum elevator car responsive to a hall call originated from the floor can be specified to improve the service for waiting passengers.

20 FIG. 16 is a block diagram showing a partial modification of the control system according to the present invention. According to this modification, two out of the three elevator cars are taken into consideration and the succeeding elevator car is accelerated when the interval between the preceding elevator car and the suc-

25 ceeding elevator car exceeds a predetermined value. Referring to FIG. 16, showing the control circuit for the elevator car A only, the adder composed of the input resistors R17A and R18A, feedback resistor

30 R19A and operational amplifier OP7A adds the time distance to the spatial distance to calculate the time interval between the elevator cars. A comparator CMA compares this time interval with a reference time interval TS and ceases to deliver its output when the time interval becomes larger than the reference time interval TS. The output from the comparator CMA is applied as one of inputs to AND elements F1UA to F9UA and F10DA to F2DA which determine the response to respective hall calls. Signals HC1UA to HC9UA and

35 HC10DA to HC2DA are applied as another input to these AND elements when hall calls are originated from the corresponding floors. The AND element applied with both these two signals delivers an output and the elevator car A is decelerated to stop at the floor

40 from which the hall call is originated. The elevator car A is stopped in response to the hall call when an output appears from the AND elements F1UA to F10DA, but it does not respond as a rule to all the ahll calls when no output appears from the AND elements. The response of the elevator car A to forward hall calls originated from the floors lying with a predetermined range may be limited without limiting the response of the elevator car A to all the hall calls. Similar means are pro-

45 vided for the elevator cars B and C.

50 Therefore, the succeeding elevator car is accelerated to maintain a reasonable interval between it and the preceding elevator car when the interval between the succeeding elevator car and the preceding elevator car exceeds a predetermined value which is variable as required. In the present embodiment, mere detection of the spatial distance between the elevator cars can attain the desired control to a certain extent. However,

55 60 65

the control can be improved by detecting the time distance in addition to the spatial distance taking into consideration the number of stoppages of the succeeding elevator car.

FIG. 17 is a block diagram showing another partial modification of the embodiment according to the present invention. According to this modification, two of the three elevator cars are taken into consideration and the preceding elevator car is accelerated when the time interval between the preceding elevator car and the succeeding elevator car becomes less than a predetermined value. Referring to FIG. 17, showing the control circuit for the elevator car A only, the adder composed of the input resistors R17A and R18A, feedback resistor R19A and operational amplifier OP7A adds the time distance to the spatial distance to calculate the time interval between the elevator cars. A comparator CMA compares this time interval with a reference time interval TS and ceases to deliver its output when the time interval becomes less than the reference time interval TS. The output from the comparator CMA is applied as one of inputs to AND elements F1UA to F9UA and F10DA to F2DA which determine the response to respective hall calls. Signals HC1UA to HC9UA and HC10DA to HC2DA are applied as another input to these AND elements when hall calls are originated from the corresponding floors. The AND element applied with both these two signals delivers an output and the elevator car A is decelerated to stop at the floor from which the hall call was originated. The elevator car A is stopped in response to the hall call when an output appears from the AND elements F1UA to F10DA, but it does not respond as a rule to all the hall calls when no output appears from the AND elements. The response of the elevator car A to forward hall calls originating from a plurality of floors may be limited without limiting the response of the elevator car A to all the hall calls. Similar means are provided for the elevator cars B and C.

Thereafore, the preceding elevator car is accelerated to maintain a reasonable interval between it and the succeeding elevator car when the interval between the preceding elevator car and the succeeding elevator car becomes less than a predetermined value which can be varied as required. According to the present embodiment, the control of the interval between elevator cars can be more satisfactorily attained due to the fact that the number of stoppages of the succeeding elevator car is taken into consideration of detecting the time distance in addition to the spatial distance instead of merely detecting the spatial distance in calculating the interval between elevator cars.

What we claim is:

1. An elevator control system for controlling a plurality of elevator cars servicing a plurality of service floor landings comprising:

interval detecting means provided for each elevator car for detecting the interval between each elevator car and a preceding elevator car which is positioned ahead of said elevator car and for generating a corresponding interval signal representing said interval,

means for providing a signal representing a desirable interval between any adjacent two of said elevator cars,

comparator means provided for each elevator car for comparing the interval signal generated by the cor-

responding interval detecting means with said signal representing said desirable interval and to produce an output signal when said interval exceeds a predetermined value over said desirable interval, accelerating means provided for each car and responsive to the output signal produced by said comparator means for accelerating the elevator car associated with said comparator means, and said interval detecting means comprising means for detecting the spatial distance between each elevator car and the preceding elevator car, means for detecting the time distance related to the number of stoppages expected for each elevator car, and means for generating a time interval signal which is proportional to the sum of said spatial distance and said time distance.

2. An elevator control system for controlling a plurality of elevator cars servicing a plurality of service floor landings comprising:

interval detecting means provided for each elevator car for detecting the interval between each elevator car and a preceding elevator car which is positioned head of said elevator car and for generating a corresponding interval signal representing said interval,

means for providing a signal representing a desirable interval between any adjacent two of said elevator cars,

comparator means provided for each elevator car for comparing the interval signal generated by the corresponding interval detecting means with said signal representing said desirable interval and to produce an output signal when said interval exceeds a predetermined value over said desirable interval, accelerating means provided for each car and responsive to the output signal produced by said comparator means for accelerating the elevator car associated with said comparator means, and

said interval detecting means comprising means for detecting the spatial distance between each elevator car and the preceding elevator car, means for detecting the time distance related to the number of stoppages expected for each elevator car while it moves through said spatial distance, and means for detecting the time interval which is the sum of said spatial distance and said time distance.

3. An elevator control system for controlling a plurality of elevator cars servicing a plurality of service floor landings comprising:

interval detecting means provided for each elevator car for detecting the interval between each elevator car and a preceding elevator car which is positioned ahead of said elevator car and for generating a corresponding interval signal representing said interval,

means for providing a signal representing a desirable interval between any adjacent two of said elevator cars,

comparator means provided for each elevator car for comparing the interval signal generated by the corresponding interval detecting means with said signal representing said desirable interval and to produce an output signal when said interval exceeds a predetermined value over said desirable interval, accelerating means provided for each car and responsive to the output signal produced by said

comparator means for accelerating the elevator car associated with said comparator means, and means for selecting, among the elevator cars that can respond to a hall call, the one nearest to the floor from which the hall call is originated and registered and for causing the selected car to respond to said hall call, and additional means responsive to the output from said interval detecting means for preventing each elevator car from responding to all of the hall calls.

4. An elevator control system as claimed in claim 3, including means for displaying at a floor from which a hall call originates the indication of the selected elevator car responding to the hall call.

5. An elevator control system for controlling a plurality of elevator cars servicing a plurality of service floor landings comprising position detecting means for detecting the positions of the respective cars, hall call selecting means for selecting hall calls for service one at a time in the order received, interval detecting means responsive to said position detecting means and said hall call selecting means for detecting the backward interval between a specific floor providing a selected hall call and each of the elevator cars, minimum interval selector means for selecting the minimum of a plurality of backward intervals, gating means for selectively connecting said interval detecting means to said minimum interval selector means, acceleration signal generator means for generating respective acceleration signals to control movement of said elevator cars, said acceleration signals being applied to said gating means when generated to inhibit application of the backward interval associated with a particular elevator car to said minimum interval selector means, and elevator car control means for actuating that elevator car designated by the output of said minimum interval selector means to respond to said selected hall call.

6. An elevator control system as defined in claim 5 wherein said hall call selecting means includes a hall call register for storing received hall calls and an interval calculating order selector for selecting hall calls from said hall call register one at a time in the order received.

7. An elevator control system as defined in claim 6 wherein said interval detecting means includes an individual interval detector for each elevator car connected to receive the output of said interval calculating order selector and said position detecting means includes a position detector for each elevator car having its output connected to an associated interval detector.

8. An elevator control system as defined in claim 7 wherein said gating means includes a first set of gates each connected to one of said interval detectors and a second set of gates connected to said first set of gates and said minimum selector means, said acceleration signals being applied to said second set of gates, and further including interval calculating commander means responsive to said interval calculating order selector for actuating said first and second sets of gates in timed sequence.

9. An elevator control system as defined in claim 8 wherein said acceleration signal generator means includes further interval detecting means responsive to said position detecting means for detecting the interval between a preceding elevator car and a succeeding elevator car, and accelerating means responsive to the

output from said further interval detecting means for accelerating the succeeding elevator car when the interval between the elevator cars exceeds a predetermined value.

5 10. An elevator control system as defined in claim 9 wherein said further interval detecting means includes means for detecting the spatial distance between the preceding elevator car and the succeeding elevator car, means for detecting the time distance related to the 10 number of internally initiated stoppages expected for the succeeding elevator car and means for generating a time interval signal which is proportional to the sum of said spatial distance and said time distance.

11. An elevator control system for controlling at least 15 three elevator cars servicing a plurality of service floor landings comprising:

first interval detecting means for detecting a first interval between each elevator car and preceding elevator car which is positioned ahead of said each elevator car and for generating a first interval signal representing said first interval,

second interval detecting means for detecting a second interval between each elevator car and the elevator car which is succeeding said elevator car and for generating a second interval signal representing said second interval,

comparator means provided for each elevator car to compare the first interval signal with the second interval signal with respect to each elevator car and to produce an output signal when said first interval signal exceeds by a predetermined value said second interval signal, and

means responsive to said output signal produced by said comparator means for preventing the elevator car corresponding to said comparator means from responding hall calls.

12. An elevator control system as claimed in claim 11, in which said first interval detecting means detects the spatial distance between each elevator car and the preceding elevator car, and said second interval detecting means detects the spatial distance between each elevator car and the succeeding elevator car.

13. An elevator control system as claimed in claim 11, in which said first interval detecting means detects the time interval which is the sum of the spatial distance between each elevator car and the preceding elevator car and the time distance related to the number of stoppages expected for each elevator car, and said second interval detecting means detects the time interval which is the sum of the spatial distance between each elevator car and the succeeding elevator car and the time distance related to the number of stoppages expected for the succeeding elevator car.

14. An elevator control system for controlling at least three elevator cars servicing a plurality of service floor landings comprising:

car detecting means provided for each elevator car to detect the nearest car to each elevator car among the elevator cars which follow each elevator car, interval detecting means provided for each elevator car to detect the interval between each elevator car and the nearest one to said each elevator car, comparator means provided for each car to compare the interval detected by the interval detecting means provided for each elevator car with the interval detected by the different interval detecting means provided for a different elevator car and to

produce an output signal when said last-mentioned interval exceeds by a predetermined value said first-mentioned interval, and
 means responsive to the output signal of said comparator means for preventing the elevator car associated with said comparator means from responding to hall calls. 5

15. An elevator control system for controlling at least three elevator cars servicing a plurality of floor landings comprising:

car detecting means provided for each elevator car to detect the nearest car to each elevator car among the elevator cars which are in advance of said elevator car,
 interval detecting means provided for each elevator 15

car to detect the interval between said each elevator car and the nearest car to each elevator car, comparator means provided for each car to compare the interval detected by the interval detecting means provided for each elevator car with the interval detected by the different interval detecting means provided for a different elevator car and to produce an output signal when said first-mentioned interval exceeds by a predetermined value said last-mentioned interval, and

means responsive to the output signal of said comparator means for preventing the elevator car associated with said comparator means from responding to hall calls.
